UNITED STATES PATENT OFFICE.

LOUIS LECLERC, OF NEW YORK, N. Y.

AUTOMATIC EGG-BOILER.

No. 879,057.

Specification of Letters Patent.

Patented Feb. 11, 1908.

Application filed July 6, 1907. Serial No. 382,529.

To all whom it may concern:

Be it known that I, LOUIS LECLERC, a citizen of the Republic of France, and a resident of the city of New York, borough of Manhattan, in the county and State of New York, have invented a new and Improved Automatic Egg-Boiler, of which the following is a full, clear, and exact description.

This invention relates to automatic egg boilers, and the object of the invention is to produce a device of simple construction not involving a clock movement, which will operate to boil eggs and remove them automatically after the expiration of a predetermined period.

The invention is intended to be especially useful in kitchens of restaurants and hotels. It is also useful in private families.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a side elevation of the egg boiler, certain parts being broken away and shown in cross section; Fig. 2 is a front elevation of the device showing it with its parts in a different relation from that in which they are shown in Fig. 1; Fig. 3 is a vertical cross section through the teeter tube, which constitutes a feature of the invention; Fig. 4 is a longitudinal section through the teeter tube, a portion of the body of the tube being broken away; and Fig. 5 is a vertical section through the lower portion of a cup which constitutes a feature of the invention.

Referring more particularly to the parts, 1 represents the body of the boiler, consisting of an open pan in which water is placed in which the eggs are to be boiled. To this pan 45 a frame 2 is attached, the same having the form of a gallows and comprising oppositely disposed standards 3 formed of flat metal. These standards are offset inwardly so that they present upright extensions 4 lying parallel and near to each other as shown in Fig. 2. These extensions unite integrally at their upper ends, at which point an outwardly projecting arm 5 is attached. Between the upright extensions 4 a teeter tube 6 is pivotally

pivot screws 7 which extend through the uprights from the outer sides thereof, as indicated in Fig. 3. Within the teeter tube 6 there is placed a ball 8 of substantial weight and this ball is formed of lead or similar material. The tube 6 is supported near its middle point, and the point of support may be adjusted, for which purpose the sides of the tube are provided with a plurality of longitudinally disposed openings 9 opposite to each other, it being understood that the pivot screws or gudgeons 7 may be inserted in any of these openings. As illustrated in Fig. 1, the principal portion of the tube 6 projects at the left side, and this may be considered as the long arm of the tube. This arm is provided on its upper and lower sides with a plurality of openings 10 which are adapted to receive a removable pin 11, as indicated in Fig. 4. This pin is intended to operate as a stop to limit the movement of the ball in its movement toward the end of the long arm of the tube. The relation of this construction to the rest of the mechanism will appear more fully hereinafter. In the opposite end 80 of the tube a buffer spring 12 is mounted, which absorbs the shock if the ball is suddenly run to the opposite end of the tube when this end is lower than the long arm. To the short arm of the tube, which projects at the right as indicated in Fig. 1, a cup holder 13 is attached, said cup holder consisting of a ring 14 upon which a cup 15 seats. This ring 14 is provided with downwardly extending arms 16 which are disposed opposite to each other as shown. Between these arms there is attached a yoke pin 17, the middle portion of which is bowed upwardly as indicated in Fig. 2, so as to rest upon the upper side of the teeter tube. The cup holder 13 is supported in an upright position by means of a link bar or rack 18 which is disposed parallel to the axis of the tube, and is pivotally attached on a cross pin 19 disposed between the extensions 4. Adjacent to the cup 15 the link bar is pivotally attached between the arms 16 upon a suitable cross pin or pivot pin 20. The cross pin 19 is removable, and the link bar is provided with a plurality of longitudinally disposed openings 21 which are arranged opposite to the openings 9. From this arrangement, when the point of support of the tube is adjusted, the point of attachment of the link bar 18 to the cross pin

in connection with its attached parts, constitutes what is known as a parallel movement device. By reason of the manner in which this device supports the cup holder, it should be understood that if the cupholder descends, the cup 15 will always be held in an upright or vertical position. The cup 15 which has been referred to above, may be considered as a main cup. In addition to this main cup, I provide a feeder cup 22. This cup is supported upon a chain 23 running over guide pulleys 24 and 25 carried by the aforesaid arm 5. The guide pulley 25 is disposed near the inner end of the arm, and from this guide pulley the chain 23 extends downwardly and passes around another guide pulley 26 which is disposed near the lower portion of the extensions 4. The object in supporting the feeder cup in this manner will appear more fully hereinafter. It is sufficient at this time to say that the feeder cup is raised automatically when the eggs are put in the boiler. The mechanism for this purpose will be described more fully hereinafter.

The feeder cup 22 is provided with a tube 27 which extends upwardly within the body of the cup, the upper end of the tube being disposed near the upper edge of the cup as shown in Fig. 1. This tube projects below the bottom of the cup 22, and is connected by means of a flexible hose 28 with an opening 29 through the bottom of the cup 15. This hose 28 may be considered as a feed hose. In addition to the feed hose, the bottoms of the cups 15 and 22 are connected by a return hose 30. As indicated in Fig. 5, the hose 30 connects with the interior of the cup 15 through a restricted opening 31, while the opening 29 with which the tube 28 connects, is of much larger diameter.

Between the upright extensions 4 the frame is provided with a pair of arms 32 which project toward the right as viewed in Fig. 1. The outer extremities of these arms 45 are connected by a ratchet shaft or arbor 33 carrying a rigid ratchet wheel 34, the teeth whereof project toward the right on the upper side of the wheel, as indicated in Fig. 1. On the shaft 33 a pulley or drum 35 is provided, the same being disposed at the left as viewed in Fig. 2.

The aforesaid chain 23 after passing around the guide pulley 26, is wrapped around this drum 35 from the under side. 55 Near the ratchet wheel 34 the shaft 33 is provided with a chain wheel 36. Upon this chain wheel a chain 37 is hung, the free end of the chain supporting a counterweight 38. From the chain wheel 36 the chain 37 extends in 60 toward the frame 2 where it passes around a guide pulley 39, whence it passes downwardly and is attached to a basket 40 formed of wire gauze or similar material. It should be understood that this basket 40 is adapted 65 to be depressed into the pan 1, as indicated

in full lines in Fig. 1, so that it may hold the eggs which are to be boiled, in the boiling water. As the chain runs out, it rotates the ratchet wheel 34. In order to prevent the weight 38 from pulling the basket immediately out of the water, I provide a detent pawl 41 which is pivotally attached on a suitable bracket 42 connected to the arms 32 as indicated in Fig. 1. This pawl operates to maintain itself in engagement with the ratchet teeth by gravity. When the basket is placed within the pan or boiler 1, the weight 38 is held in an elevated position, and this weight 38 should be composed of removable sections or small weights which permit the total weight to be adjusted to suit the number of eggs in the basket. The pawl 41 is formed with a rearward extension or tail 43 which projects toward the frame and lies under the short arm of the teeter tube 6. On the under side of this teeter tube at this point, a pin 44 is provided, which is adapted to strike the tail 43 of the pawl when the short arm of the tube descends, as will be described hereinafter.

On the side of the pan 1 a bracket 45 is attached, on the upper side of which a buffer spring 46 is placed upon which the weight 38 descends, as will appear hereinafter.

The operation of the egg boiler will now be described: The parts are set in the relation shown in Fig. 1 when the eggs are to be boiled, the eggs having been placed in the basket 40. It will be understood that in order to withdraw the eggs, it will only be necessary to release the ratchet wheel 34 from its pawl 41, whereupon the counterweight 38 will descend and withdraw the eggs by raising the basket to the position in which it is shown in dotted lines in Fig. 1. At this time the feed cup 22 is supported in an elevated position; it is provided with a quantity of water, and this water finds its way through the tube 30 and the restricted opening 31 into the main cup 15. In this way the weight of the main cup which is supported by the short arm of the teeter tube, increases gradually. When it has increased sufficiently it will counterbalance the ball or the counterweight 8 which lies against the stop pin 11 in the long arm of the tube. As soon as the ball is counterbalanced in this way, the cup 15 descends, pushing down the short arm of the teeter tube. In this way the pin 44 is made to descend upon the tail 43 of the pawl 41, and the ratchet wheel 34 is released. The weight 38 then operates to withdraw the basket 40 from the boiler 1, as suggested above. At the same time the rotation of the shaft 33 unwinds the chain 23 which supports the feed cup, and this feed cup then descends to a level below that of the main cup 15. The water which has flowed into the main cup 15 will then return to the feed cup 22 through the return tube 28 and the tube 27. It will 130

take only an instant for the water to return in this manner, on account of the fact that the duct through which the water flows in this case, is quite large, as indicated in Fig. 5. By reason of the tube 27, the mouth of which is above the level of the water in the cup 22, it is not possible for the water to flow to the main cup from the feed cup through the tube 28; it must pass through the tube 30 and the restricted opening. In this way the flowing of the water when the boiler is in active operation, is restricted, and the device is enabled to operate with a relatively small quantity of water. If the eggs are to be boiled a longer time, the stop pin 11 is moved toward the outer end of the tube; if they are to be boiled a shorter time, it is moved toward the middle point of the tube, or inwardly. The effect of changing the position 20 of the pin will be readily understood, as the teeter tube simply constitutes a lever, and when the pin is moved inwardly, the force to raise the long arm and overcome the weight of the ball 8 will, of course, be proportionately less.

With an egg boiler constructed as described, the eggs may be placed in the basket and held in the water for a length of time which is determined by the position of the pin 11. As soon as this time elapses, the weight of the ball in the main cup 15 will have overbalanced the weight of the ball and thrown the tube into an opposite position, indicated in dotted lines in Fig. 1, releasing the ratchet wheel and removing the eggs in the manner described above.

Special attention is called to the means for preventing the flow of water from the feed cup to the main cup through the return tube, which is only used for a flow of the water in the reverse direction. Special attention is also called to the feature of lowering the feed cup 22 simultaneously with the withdrawing of the egg basket. On account of this arrangement, the feed cup then automatically fills and is all ready and full of water when the eggs are to be placed in the basket again.

Having thus described my invention, I claim as new and desire to secure by Letters Patent:

1. In an automatic egg boiler, in combination, an egg basket, a main cup, a feed cup adapted to drain into said main cup, means for normally supporting said feed cup above the level of said main cup, means controlled by the weight of said main cup to withdraw said basket, and automatic means for depressing said feed cup to return the water thereto when said basket is withdrawn.

2. In an automatic egg boiler, in combination, a main cup, a feed cup, hose connecting said cups, means for changing the relative position of said cups to permit a liquid to flow in either direction therebetween, and

means for withdrawing the eggs, controlled by said main cup.

3. In an automatic egg boiler, in combination, a main cup, a feed cup, means for changing the elevation of said cups, means permitting a free flow of liquid from said main cup to said feed cup, means for permitting a restricted flow of liquid from said feed cup to said main cup, and means for withdrawing the eggs, actuated by said main cup. 75

4. In an automatic egg boiler, in combination, a teeter, an adjustable weight thereupon, a cup counterbalancing said weight, means for supplying a material to said cup to weight the same, mechanism for withdrawing the eggs, normally held in check, and means for releasing said last mechanism by said cup. 80

5. In an automatic egg boiler, in combination, a frame, a teeter adjustably supported upon said frame, a weight adjustably supported on said teeter, a cup normally held in an elevated position and adapted to overbalance said weight when loaded, means for supplying a material to said cup to weight 90 the same, and mechanism for withdrawing the eggs, actuated by said teeter.

6. In an automatic egg boiler, in combination, an egg basket, a chain and counterweight tending to withdraw the same, a cup, 95 means for gradually loading said cup, means for counterbalancing said cup, and means for releasing said weight when said cup descends.

7. In an automatic egg boiler, in combination, a counterweighted main cup, a feed 100 cup, means for holding said feed cup in an elevated or depressed position with respect to said main cup, a hose connecting said cups, attached to said feed cup at a low level and through which a liquid may flow from 105 said feed cup when elevated, and a second hose connecting said cups, communicating with said feed cup at a high level whereby said hose will only permit a flow from said main cup to said feed cup, the flow through 110 said first hose being restricted so that considerable time is consumed in the flow, the flow through said second hose being free so that the return to said feed cup is quickened.

8. In an egg boiler, in combination, a main 115 cup and a feed cup, means for supporting said cups so that either may be the more elevated, hose connecting said cups and through which a liquid may flow between said cups, mechanism tending to withdraw 120 the egg and tending to lower said feed cup, and means for releasing said mechanism when said cup is loaded.

9. In an automatic egg boiler, in combination, a main cup, a feed cup having a tube 125 with its mouth at a high level therein, a hose connecting the lower end of said tube with said main cup and adapted to return a liquid from said main cup to said feed cup, a second hose adapted to conduct a liquid from 130

said feed cup to said main cup and connected with said feed cup at a low level therein, a chain wheel, a chain running over the same, an egg basket supported by said chain, a weight carried by said chain and adapted to raise the said egg basket, a ratchet wheel rigid with said chain wheel, a ratchet engaging said ratchet wheel, a pulley rigid with said chain wheel and rotating therewith, a chain winding on said pulley and supporting said

feed cup, and means for engaging said pawl when said main cup descends.

In testimony whereof I have signed my name to this specification in the presence of two subscribing witnesses.

LOUIS LECLERC.
